UNITED STATES PATENT OFFICE

2,552,080

PICKUP HOLDER FOR ROUNDED BOTTOM
PAPER CUPSWalter E. Amberg, Beverly Shores, Ind., assignor
to Lily-Tulip Cup Corporation, Chicago, Ill., a
corporation of Delaware

Application June 30, 1948, Serial No. 36,208

3 Claims. (Cl. 65—61)

1

This invention is directed to a pickup holder for paper cups and more particularly to a pickup holder for rounded bottom conical paper cups and also to the combination of and the cooperative relationship between a rounded bottom conical paper cup and a pickup holder therefor.

My co-pending application Ser. No. 789,608 filed December 4, 1947, now Patent No. 2,473,840 granted June 21, 1949, discloses and claims a rounded bottom conical paper cup and various methods of forming the same, as by plaiting the apex of a conical paper cup in a series of plaits. Such a paper cup has many advantages over a conventional conical paper cup. For example, all substances served therein may be made accessible to a conventional spoon, substances may be readily mixed therein, and danger of injury by the sharp apex of conventional conical paper cups is eliminated. Such paper cups may also be readily nested or stacked for storage purposes.

However, it is desirable in using such paper cups to support the rounded bottoms thereof to prevent them from being punctured or damaged and to prevent the plates thereof from becoming extended in the event that the rounded bottoms should be forcefully engaged by a spoon. It is also desirable automatically to pick up such a paper cup from a stock of nested paper cups by the cup holder which receives the paper cup.

The principal object of this invention is to provide a pickup holder for rounded bottom conical paper cups wherein a rounded bottom conical paper cup is readily received therein, wherein a rounded bottom conical paper cup may be automatically picked up from a stack of nested paper cups thereby, wherein the rounded bottom of the rounded bottom conical paper cup is effectively supported therein, and wherein damaging or puncturing or extending the plaits of the rounded bottom of the paper cup is effectively prevented when the paper cup is in use in the pickup holder.

In carrying out this object of the invention the pickup holder preferably includes a base portion and a receptacle portion for receiving the rounded bottom conical paper cup, a transverse partition in the holder having a concave surface for receiving and supporting the rounded bottom of the paper cup, and gripping fingers in the holder adjacent the concave surface to be engaged by the rounded bottom conical paper cup when received in the holder for automatically gripping the side wall of the paper cup adjacent the rounded bottom thereof.

Further objects of this invention reside in the

2

details of construction of the pickup holder for rounded bottom conical paper cups, the cooperative relationship between the component parts and the combination of and the cooperative relationship between the pickup holder and the rounded bottom conical paper cup received thereby.

Other objects and advantages will become apparent to those skilled in the art upon reference to the accompanying specification, claims and drawing in which:

Figure 1 is a vertical sectional view of the pickup holder with a rounded bottom conical paper cup received therein;

Figure 2 is a sectional view similar to Figure 1, but omitting the rounded bottom conical paper cup;

Figure 3 is a perspective view of the transverse partition member included in the pick up holder;

Figure 4 is a horizontal sectional view taken substantially along the line 4—4 of Figure 1 and

Figure 5 is a view similar to Figure 1, but illustrating one of the rounded bottom conical paper cups disclosed and claimed in my aforementioned co-pending application.

A rounded bottom conical paper cup is generally designated at 10 and it includes a conical side wall 11 and rounded bottom 12. If desired the paper cup may be provided with a rim 13.

The pick up holder is generally designated at 15 and is shown to be a two piece holder. It includes a receptacle portion 16 which is generally conical in configuration. The lower part of the receptacle portion 16 preferably is externally provided with an annular recess 17 which in turn is provided with an inwardly and downwardly extending flange 18.

The pick up holder also includes a base portion 20, the upper part 21 of which is preferably flared outwardly as at 21. The base portion 20 is secured to the receptacle portion 16 by telescopically receiving the recess 17 within the flared upper part 21 of the base portion 20. The juncture of the base and receptacle portions forms a throat in the holder. The receptacle and base portion may be formed of any suitable material such as plastic or metal. In the latter event, the receptacle and base portions may be formed by spinning. The telescopic juncture between the base and receptacle portions may be maintained by a pressed fit or by welding the portions together.

The pick up holder 15 also includes a transverse partition member 23 located in the throat of the holder and which is preferably made of a resil-

ient material such as rubber composition, "Tygon," or other suitable resilient material. The partition member 23 includes a transverse partition 24 having a concave surface 25 which is adapted to receive and support the rounded bottom 12 of the conical paper cup 10. The transverse partition 24 may be provided with a central hole 26 to provide a drain for any liquid which might collect in the concave surface 25. This hole 26 greatly facilitates the cleaning and drying of the pick up holders.

The partition member 23 also includes a plurality of resilient fingers 27 which are located above and adjacent to the concave surface 25. The resilient fingers are adapted to be distorted by the rounded bottom conical paper cup when it is received in the holder for the purpose of automatically gripping the side wall 11 of the paper cup adjacent the rounded bottom thereof. The resilient fingers 27 normally take the position illustrated in Figure 2, but are distorted to the position illustrated in Figure 1 when the rounded bottom conical paper cup is received in the holder. As is illustrated in Figure 1, the resilient fingers 27 are gripping the side wall of the paper cup adjacent the rounded bottom thereof.

The outside of the partition member 23 is tapered to conform generally to the flared upper part 21 of the base portion 20 so that movement of the partition member downwardly through the base portion 20 is effectively prevented. The upper side of the partition member 23 is provided with an annular rib 28 which is adapted to be received under the inwardly and downwardly extending flange 18 of the receptacle portion 16.

In assembling the pickup holder, the partition member 23 is inserted in the flared upper part of the base portion and then the receptacle portion is telescopically received in the base portion. The inwardly and downwardly extending flange 18 on the receptacle portion and the flared part of the base portion operate effectively to retain the partition member within the holder.

In use the pickup holder is placed over the end cup of a stack of nested rounded bottom conical paper cups. In so doing, the paper cup is received in the receptacle portion of the pickup holder with the rounded bottom thereof engaging the concave surface 25 of the partition. The resilient gripping fingers 27 are distorted by the paper cup and operate automatically to grip the side wall of the paper cup adjacent the rounded bottom thereof. The paper cup thereby is removed from the stack of nested cups by the holder and the paper cup is firmly held within the holder.

The paper cup thus held by the holder may be supplied with any suitable substance and because of the rounded bottom mixing of the substance by a spoon is readily accommodated. Further, in the use of the cup substantially all of the substance may be removed from the cup by a spoon, this being afforded by the rounded bottom construction.

The concave surface in the transverse partition operates effectively to support the rounded bottom so that it cannot be damaged or punctured if a spoon is brought forceably in contact therewith. When it is desired to remove the paper cup from the holder, all that is necessary is to pull the same therefrom, this removing action being permitted by the resilient fingers.

The rounded bottom paper cup 10 may be formed as described in the aforementioned co-pending application by plaiting the base of a

conical paper cup in a series of plaits which plaits are illustrated at 30 in Figure 5. The concave surface 25 in the transverse partition therefore operates in addition to preventing puncturing or damaging of the rounded bottom to prevent plaits 30 from becoming extended.

While for purposes of illustration, one form of this invention has been disclosed, other forms thereof may become apparent to those skilled in the art upon reference to this disclosure, and therefore, this invention is to be limited only by the scope of the appended claims.

I claim as my invention:

1. A pickup holder for a rounded bottom conical paper cup comprising, a base portion having a flared upper part, a receptacle portion telescopically received in the flared upper part of the base portion and provided with an internal flange adjacent the bottom thereof, the receptacle portion adapted to receive a rounded bottom conical paper cup with the rounded bottom thereof extending into the base portion, and a transverse partition member formed of resilient material received in the flared upper part of the base portion and held in place therein by the internal flange adjacent the bottom of the receptacle portion and including a transverse partition having a concave surface for receiving and supporting the rounded bottom of the rounded bottom conical paper cup and including resilient gripping fingers adjacent the concave surface of the partition to be distorted by the rounded bottom conical paper cup when received in the holder for automatically gripping the side wall of the rounded bottom conical paper cup adjacent the rounded bottom thereof.

2. A substantially hollow pickup holder for a rounded bottom conical paper cup comprising, a base portion and a substantially conical cup receptacle portion joining the base portion, the juncture forming a throat between the base and receptacle portions, said receptacle portion receiving and supporting a rounded bottom conical paper cup with the rounded bottom of the paper cup extending into the throat, a transverse partition in the throat of the holder having a concave surface for receiving and supporting the rounded bottom of the paper cup, and inwardly extending resilient gripping fingers in the throat of the holder adjacent the concave surface of the transverse partition to be distorted by the paper cup when received in the holder for automatically gripping the side wall of the rounded bottom conical paper cup adjacent the rounded bottom thereof.

3. A substantially hollow pickup holder for a rounded bottom conical paper cup comprising, a base portion and a substantially conical cup receptacle portion joining the base portion, the juncture forming a throat between the base and receptacle portions, said receptacle portion receiving and supporting a rounded bottom conical paper cup with the rounded bottom of the paper cup extending into the throat, and a transverse partition member secured in the throat of the holder and formed of resilient material and including a transverse partition having a concave surface for receiving and supporting the rounded bottom of the paper cup and including inwardly extending resilient gripping fingers adjacent the concave surface of the partition to be distorted by the paper cup when received in the holder for automatically gripping the side wall of the

rounded bottom conical paper cup adjacent the rounded bottom thereof.
